BOAT

Ralph R. O'Brien, Columbia, S. C.

Application May 10, 1939, Serial No. 272,903

11 Claims. (Cl. 37—76)

My invention relates to boats.

An important object of the invention is to provide a boat or barge with means whereby the same may be navigated in shallow streams otherwise unnavigable by the same.

A further object of the invention is to provide a cargo carrying boat with digging or scraping means operating near the bottom of the boat, to remove raised portions or obstructions in the bed 10 of a shallow stream or river, to prevent the boat being grounded.

A further object of the invention is to so arrange the blades that they are brought in succession into digging or scraping engagement with the obstruction.

A further object of the invention is to provide means of the above-mentioned character which may operate to dig or remove the silt or sand, while the barge is being propelled.

A further object of the invention is to provide means for introducing water under pressure, in close proximity to the traveling blade, to aid the same in digging away the silt or sand.

A further object of the invention is to provide 25 a barge of the above-mentioned character having an upper deck or cover, arranged above the digging or scraping devices and adapted to receive thereon the cargo.

Further objects and advantages of the invention will be apparent during the course of the 30 following description.

In the accompanying drawings forming a part 35 of this application and in which like numerals are employed to designate like parts throughout the same,

Figure 1 is a side elevation of a cargo carrying barge embodying my invention,

Figure 2 is a plan view of the same,

Figure 2a is a transverse section taken on line 40 2a—2a of Figure 2,

Figure 3 is a longitudinal section taken on line 3—3 of Figure 2,

Figure 4 is a similar view taken on line 4—4 of Figure 2,

Figure 5 is a transverse section taken on line 45 5—5 of Figure 4,

Figure 6 is an edge elevation of a portion of one of the endless scraping or digging elements, associated elements being in section,

Figure 7 is a plan view of the same,

Figure 8 is a transverse section taken on line 50 8—8 of Figure 7,

Figure 9 is a perspective view of one of the scraping or digging blades,

Figure 10 is a front elevation of the barge,

Figure 11 is a perspective view of the spraying system, and,

Figure 12 is a perspective view of the gearing.

In the drawings, wherein for the purpose of illustration is shown a preferred embodiment of my invention, the numeral 10 designates a boat, barge, or floating body which is relatively shallow and has a flat bottom 11. The boat or barge also has a flat top or deck 12. The numeral 13 designates the bow of the boat or barge, which is 10 inclined upwardly in a forward direction, while the numeral 14 designates the stern of the boat which is inclined upwardly in a rearward direction. The numeral 15 designates an upper horizontal platform or deck, preferably extending 15 throughout the entire length of the deck 12, and supported by transverse bars 16, in turn resting upon and secured to angle-irons 17 and I-beams 18. The angle-irons 17 and I-beams 18 are rigidly secured to the deck 12, thus affording 20 spaces or passages 19, extending longitudinally of the boat or barge.

Arranged within the several longitudinal passages 19 are tracks or guides 20, which extend longitudinally over the deck 12, about the bow 25 13 and stern 14, and beneath the bottom 11, and are rigidly secured to these parts, by bolts or the like. Each track or guide comprises a pair of spaced angle-irons 21, rigidly attached to the boat or barge 10. The webs 22 of the angle-irons 30 21 are vertically arranged and these vertical webs 22, Figure 8, are connected at equidistantly spaced points by horizontal shafts 23, passing through openings 24, and held in place by suitable means, such as washers 25 and cotter pins 26. The 35 shafts 23 carry rollers or sleeves 27, rotatable thereon.

Endless digging or scraping devices operate upon and within the tracks or guides 21, and correspond in number and arrangement with relation thereto. Each endless digging or scraping device includes an endless chain 28, including pairs of link 29 and 30, pivotally connected by pins 31, carrying spacers 32. Welded or otherwise rigidly secured to selected links 30 are attaching blocks 33. These blocks are disposed upon the outer sides of the links 30, and project above or outwardly of the same for a substantial distance, while the inner ends of the blocks terminate short of the inner edges of the links 30. 45 The attaching blocks 33 operate within and between the webs 22, and are adapted to slidably engage these webs, but the all-over distance between the outer faces of the blocks 33 is slightly less than the all-over distance between the inner 50 55 links 30.

faces of the webs 22, so that the parts will not bind in operation, as clearly shown in Figure 8. The links 29 and 30 travel in contact with the rollers 27, and retain the blocks 33 spaced from these rollers, as shown. The pairs of blocks 33 are preferably equidistantly spaced in each endless digger or scraper.

Secured to the outer ends of each pair of blocks 33 is a digger or scraper, which is L-shaped in cross-section and comprises a horizontal web 34 and a vertical blade 35. The blade is provided upon its trailing side with a horizontal stiffening web 36, formed integral therewith. The horizontal web 34 is mounted upon the outer ends of the attaching blocks 33 and is rigidly secured thereto by pairs of bolts 37 or the like.

As more clearly shown in Figure 2 of the drawings the blades 35 are preferably arranged in V-shaped groups, and these groups are spaced longitudinally of the boat or barge. The blades in each arm of the V-shaped group are also spaced longitudinally of the boat or barge and are also spaced transversely of the boat or barge, providing spaces for the I-beams 18, Figure 2a. These blades need not contact with the I-beams.

The endless chains 28, constituting sprocket chains, pass over and engage vertical sprocket wheels 38, rigidly mounted upon a horizontal transverse shaft 39, arranged near and above the deck 12. The shaft 39 is journaled in bearings 40, Figure 5, preferably welded to the angle-irons 21 or otherwise rigidly attached thereto. At the bow of the boat or barge 10, the endless sprocket chains 28 pass about sets of sprocket wheels 41, rigidly mounted upon a horizontal transverse shaft 42, journaled in bearings corresponding to the bearings 40. The endless chains also pass about sets of sprocket wheels 43 rigidly secured to a transverse shaft 44, journaled in bearings corresponding to the bearings 40. The shafts 42 and 44 are arranged near the deck 12. Disposed near the bow 13 and adjacent to the forward end of the bottom 11 is a set of sprocket wheels 45, mounted upon a transverse shaft 46, journaled in bearings corresponding to the bearings 40. The sprocket chains also pass about sets of sprocket wheels 47, arranged at the lower end of the stern 14 and adjacent to the rear end of the bottom 11 and these sprocket wheels 47 are rigidly mounted upon a transverse shaft 48 journaled in bearings corresponding to the bearings 40. Sets of sprocket wheels 49 are arranged near the upper end of the stern 14 and near the rear end of the deck 12 and are carried by transverse shafts 50, journaled in bearings corresponding to the bearings 40. The sprocket chains 28 pass about and engage the sprocket wheels 49, as shown. The several sets of sprocket wheels serve to guide the sprocket chains, and hence the guide rollers 27 which might occur at these points are omitted. These sets of sprocket wheels, excepting the sprocket wheels 38, are simply guides and do not propel the endless sprocket chains.

The numeral 51 designates a prime mover, such as a Diesel engine, which is suitably mounted upon the upper deck. This engine drives a horizontal longitudinally extending shaft 52, having a beveled gear 53 rigidly secured thereto, engaging a beveled gear 54, rigidly mounted upon a vertical shaft 55. This vertical shaft drives a beveled gear 56, engaging a beveled gear 57, secured to a horizontal shaft 58. The shaft 58 is connected with a horizontal shaft 59, through the medium of reversible gearing 60. The shaft 59 drives a beveled gear 61, which in turn engages and drives a bevel

eled gear 62, rigidly mounted upon the shaft 39. It is thus seen that power is applied to the shaft 39 to drive it, and this shaft in turn drives the several sprocket chains 28 through the medium of the sprocket wheels 38.

Means are provided to propel the boat or barge, comprising paddle wheels 63, located at the stern of the boat or barge, and carried by a shaft 64, rotatably supported in arms 65, secured to the boat or barge. Near its center the shaft 64 has a beveled gear 66, driven by a beveled gear 67, rigidly secured to a diagonal shaft 68, having a beveled gear 69 secured to its upper end. This beveled gear 69 is driven by a beveled gear 70 rigidly mounted upon a shaft 71, connected with and driven by the shaft 52, through the medium of reversible gearing 72.

The barge is equipped with a rudder 73, operated by any suitable means.

The numeral 74 designates a cabin enclosing the engine 51 and associated elements.

The I-beams 18 are disposed only upon the top of the barge or deck 12. Pipes 75 extend longitudinally between the I-beams and may be secured thereto. These pipes extend downwardly about the bow 13 and are equipped at their ends with nozzles 76, located in a straight horizontal row adjacent to the forward end of the bottom 11. These nozzles serve to spray water under pressure in close proximity to the blades 35 as these blades engage with the hill or bank, thus aiding the blades in digging or scraping off the hill or bank and in working the sand or the like rearwardly. The blades 35 are disposed in transverse V-shaped groups, so that the blades in each group moving longitudinally of the barge engage the hill or bank in succession. The nozzles are arranged in a straight transverse row, so that jets of water are projected under pressure in proximity to each blade as it engages the bank or hill in succession. The pipes 75 extend rearwardly and are connected with a common pipe 79, having connection with the outlet side of a rotary water pump.

The operation of the apparatus is as follows:

The boat or barge may be loaded with cargo placed upon the upper deck 15. The engine 51 drives the paddle wheels 63 which propel the barge. When the boat or barge 10 approaches a hill or bank A in the bed of the shallow stream, the successive transverse groups of blades 35 engage the bank, and dig or scrape the same away and drag the loose material rearwardly. This action is aided by the spraying of the water under pressure from the nozzles in proximity to the blades 35. During this digging or cutting operation the travel of the barge may be stopped in whole or in part, and as the hill is cut away sufficiently to permit of the floating of the boat or barge the same is propelled forwardly, and the successive groups of blades dig or scrape into the hill A until it is entirely dug or scraped away. In this manner the barge may navigate shallow streams which would otherwise be unnavigable.

It is to be understood that the form of my invention herewith shown and described is to be taken as a preferred example of the same and that various changes in the shape, size and arrangement of parts may be resorted to without departing from the spirit of my invention or the scope of the subjoined claims.

Having thus described my invention, what I claim is:

1. A barge or the like, endless guides secured to the barge, endless flexible elements operating within the guides, means to drive the endless

- flexible elements, transverse sets of blades spaced longitudinally of the endless flexible elements, the blades in each set being separate and secured to the adjacent endless flexible element, 5 the blades in the transverse sets being transversely spaced, a deck arranged above the blades, and means mounted upon the barge to support the deck and extending into the spaces between the blades.
- 10 2. A barge or the like, endless guides extending longitudinally about the barge and secured thereto and being transversely spaced, endless flexible elements engaging the guides, transverse groups of blades spaced longitudinally of the ends 15 less flexible elements, the blades in each group being secured to the adjacent endless flexible elements and having their ends spaced transversely of the barge, supporting members secured to the barge and extending longitudinally thereof and 20 arranged between the ends of the blades, and a deck carried by the supporting members.
3. A barge or the like, endless guides extending longitudinally around the barge and secured thereto and being transversely spaced, endless flexible elements operating within the guides, substantially V-shaped groups of blades spaced longitudinally of the endless flexible elements, the blades in each V-shaped group being spaced and secured to the adjacent flexible elements, 25 30 and means to drive the flexible elements.
4. A barge or the like, endless guides extending longitudinally around the barge and secured thereto and being transversely spaced, endless flexible elements operating within the guides, means to drive the flexible elements, transverse groups of blades spaced longitudinally of the flexible elements, the blades in each group being longitudinally and transversely spaced with respect to the barge and secured to the adjacent 35 40 flexible elements, supporting members secured to the top of the barge and arranged between the spaced ends of the blades in said groups and extending above the blades, and means mounted upon the supporting members and providing a deck above the blades.
5. A barge or the like, a guide secured to the barge and including spaced guide members, rollers mounted between the guide members, a chain operating between the guide members and 50 engaging the rollers and including links, attaching blocks secured to certain of the links and disposed between the chains and the guide members, blades mounted upon and secured to the attaching blocks and means to drive the 55 chain.
6. A barge or the like, a guide secured to the barge and including spaced guide members, rollers mounted between the guide members, a chain operating between the guide members and engaging the rollers and including pairs of links, pairs of attaching blocks secured to certain pairs of links and disposed between the chain and the guide members, a transverse blade mounted upon each pair of attaching blocks and provided upon 60 65 its trailing side with a stiffening rib, bolts for securing the blade to the pair of attaching blocks and means to drive the chain.
7. A barge or the like, endless guides extending about the barge and secured thereto, each guide including a pair of spaced guide members and rollers arranged between and secured to the guide members, endless chains operating within the guides and engaging the rollers, attaching blocks secured to the chains and arranged between them and the guide members, blades secured to the attaching blocks, and means to drive the chains. 5 10
8. A barge or the like, supporting members secured to the top of the barge and extending longitudinally of the same and transversely spaced to provide passages, endless guide devices extending longitudinally about the barge and having their upper portions arranged within the passages, endless flexible elements operating within the guides, blades operating within the 15 20 passages and secured to the endless flexible elements means to drive the flexible elements, and a supporting structure mounted upon the supporting members above the passages. 25
9. A barge or the like, supporting members secured to the top of the barge and extending only longitudinally of the top and transversely spaced to provide passages, endless guide devices extending longitudinally about the barge 30 and having their upper portions arranged within the passages, the endless guide devices extending around the bow and stern of the barge and transversely spaced, blades operating within the passages, flexible endless elements engaging the guides and carrying the blades, pipes extending about the bow and arranged between the guides and provided at their free ends with nozzles arranged adjacent to the bottom of the barge, the nozzles projecting streams of water in proximity to the blades when they engage an obstruction, means to supply water under pressure to the pipes, and a deck mounted upon the supporting members and arranged above the guides for holding cargo. 35 40 45
10. A barge having a top, supporting members secured to the top of the barge and spaced to provide passages, endless flexible elements operating within the passages, guide means for the endless flexible elements, blades carried by the endless flexible elements and movable through the passages, a deck arranged above the passages and covering the same and mounted upon the supporting members, and means to drive the endless flexible elements. 50
11. A barge or the like, a deck secured to the upper portion of the barge and forming a passage, an endless flexible element having a run traveling through the passage beneath the deck, means mounted upon the barge to support and guide the endless flexible element, blades secured to the endless flexible element and operating through the passage, and means to drive the endless flexible element. 55 60 65
